Primary Examiner — Kevin K. Rudzinski*Assistant Examiner* — Richard E Yenchesky(74) *Attorney, Agent, or Firm* — A.C. Entis-IP Ltd.; Allan C. Entis(57) **CLAIM**

What is claimed is the ornamental design for a laundry basket, as shown and described.

DESCRIPTION

FIG. 1 is a perspective back view thereof, showing our new design;

FIG. 2 is a perspective front view thereof;

FIG. 3 is a rear view thereof;

FIG. 4 is a front view thereof;

FIG. 5 is a side view thereof;

FIG. 6 is a side view thereof;

FIG. 7 is a top view thereof; and,

FIG. 8 is a bottom view thereof.

The Broken lines illustrate portions of the design that are disclaimed and do not form part of the claimed design.

1 Claim, 8 Drawing Sheets(56)
